UNITED STATES PATENT OFFICE

2,510,910

APPARATUS FOR FLUSHING TOILETS

Karol Hubert Nicolaas Schulpen, The Hague,
NetherlandsApplication September 24, 1946, Serial No. 698,933
In the Netherlands September 24, 1945

2 Claims. (Cl. 4—26)

1

My invention relates to an improved toilet flushing apparatus.

The main object of my invention is to provide an efficient and noiseless flushing apparatus of simple construction.

Another object of my invention is to provide a flushing apparatus having a new and elegant appearance, which can be mounted at any desired place.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a schematical view of one embodiment of my improved apparatus;

Fig. 2 is a section according to line II—II in Fig. 1;

Fig. 3 is a view of a second embodiment;

Fig. 4 is an isometric view of a mechanism for actuating the valve.

A water tank 1 having one or more elastic walls, hence e.g., a rubber bag is provided with a feed or inlet pipe 2 and a discharge end 3. The inlet pipe 1 may be connected in any suitable manner with a water pressure line.

The bag 1 is enclosed in a casing 4 of sheet metal, plastic material, ceramic material, or other suitable material and supported by a bottom member 5.

The discharge end 3 is connected to a discharge pipe 6 of elastic material such as a rubber hose leading to a toilet bowl (not shown). The cross section of this hose or at least part of it preferably has an oval cross section as shown in Fig. 2.

At one side the hose 6 is supported by a counter support 7 secured to a base plate 8 (in Fig. 1) or by brackets 9 and 10 to the wall of the casing 4. The plate 8 can be mounted at any desired place to a wall by means of screws 11.

In Fig. 1 a lever 12 is pivoted to the plate 8 at 13. One arm 12a of said lever 12 is fork-shaped (Fig. 2) and carries a roller 14 adapted to cooperate with the hose 6 and to deform same against the support 7 thus closing the hose by a pinching action.

The other arm 12b of lever 12 carries a handle 15 pivoted to the arm 12b at 16.

Said handle 15 may be moved to the position shown in dotted lines in Fig. 1.

In Figure 1 the lower end of hose 6 is connected to an outlet nozzle 17 by means of a spring ring 17a.

2

The nozzle 17 is secured to the plate 8 by means of a bracket or clamp 18.

The pivot 13 of lever 12 can be adjusted in a slot 19, such that the roller 14 can be adjusted 5 to cooperate with another part of the hose 6. This is useful when there is some wear and tear of a particular part of the hose 6.

The support 7 and the pivot 13 may be mounted onto frame plate 20 shown in dotted lines in Fig. 1. 10 This plate can integrally be shifted with respect to the hose 6 and then secured by means of set screws 21.

The base plate 8 with all the parts mounted thereon may be constructed as a handy unit.

15 However it is also possible to combine the roller 14, the hose 6 and the support 7 with the lever 12 to a structural unit with a casing enclosing also the waterbag.

This is shown in Fig. 3 which will be described 20 later on.

In operation (Fig. 1) the roller 14 is normally in the position shown in dotted lines at 14a in Fig. 1, thus closing the hose 6 against support 7. The bag 1 is filled with water and expanded. On 25 pressing the handle 15 the hose is opened, so that the bag 1 may collapse and is discharged with some force determined by the pressure of the bag walls on the water volume in the bag 1. Thus, the toilet bowl is efficiently flushed in a noiseless 30 manner.

The user after pressing the handle 15 releases same and the weights and sizes of the arms of lever 12 are so chosen that the roller 14 has a tendency to move in direction of the hose 6, to deform and close same when the pressure in the 35 hose decreases. The roller 14 is supported in this action by the pressure of the water flowing in the bulge 6a of the hose.

The closing end position of the roller 14 may 40 be determined by a stop (not shown) or a design such that the roller 14 is clamped in an end position against the hose 6 and the support 7.

The speed of the automatic closing action depends on the weight and proportions of lever 12 45 and the parts attached thereto.

When the handle 15 is raised to the position shown in dotted lines and then actuated the lever 12 with roller 14 during the closing period due to the heavier weight at the side of arm 12 50 will fall down with heavier pressure and the hose 6 will be sooner closed. Thus a flushing with smaller quantities of water is obtained.

In Fig. 3 the entire mechanism and the bag 1 is 55 enclosed in a casing 4.

The pivot 13 of lever 12 is arranged in a bracket 22 secured to the casing 4.

The arm 12b of lever 12 is connected to the shaft 23 of a press button 24 by means of a pin and slot connection 25, 25a.

The shaft 23 is guided in a sleeve 26 mounted in the casing 4. The bottom part 4a of the casing is removable.

A spring 28 is attached at one end to arm 12a of lever 12 and at the other end to a lug 27 of bracket 9.

30 is a pipe for discharging liquid, which may have entered the casing 4.

In this embodiment the lever 12 with roller 14 is spring urged.

The spring mechanism may be so constructed that the effective load on the lever 12, i. e., the momentum on said lever with respect to its pivot 13 may be varied.

This is shown in Fig. 4.

One end of the spring 28 is attached to a block 31, which can be shifted in a slot 31a in arm 12a of lever 12.

The ends of the shafts 23 and 23a of two buttons 24 and 24a are provided with slots 36 and 37 and connected by links 32 and 33 to the arms 35 and 34 respectively, of a shiftelever.

In the position of the mechanism shown in Fig. 4 on pressing button 24a link 33 swings lever arm 34 to the right and shifts block 31 also to the right. The spring 28 now has its highest tension and the roller closes hose 6 at high speed after actuation of lever 12, which happens in the later part of the inward stroke of button shaft 23a when the left hand end of the slot 37 in said shaft engages the pin 25 at lever arm 12b.

On pressing button 24 due to the fact that pin 25 at lever 12b is already at the left end of slot 36 in button shaft 23, the lever 12 is immediately swung about its pivot 13 without a previous adjustment of the spring 28 which exerts the smallest momentum on lever arm 12a.

The closing period of roller 14 is greater and more water is discharged.

Having now described the nature of my invention and the objects thereof what I claim is:

1. An apparatus for flushing a toilet comprising: a closed tank having an inlet arranged for connection with a water pressure line and having an outlet, a discharge pipe, one end of said discharge pipe being connected to said outlet, the other end of said discharge pipe being arranged for connection with a toilet, at least a portion of said discharge pipe being made of elastic material, an abutment arranged adjacent said elastic portion of said discharge pipe, a movable pressure member arranged for cooperation with said elastic portion of said discharge pipe, biasing means connected with said movable pressure member, said biasing means being operative to

urge said movable pressure member normally against said elastic portion of said discharge pipe so as to close same by a pinching action in cooperation with said abutment, at least a portion of the walls of said closed tank being made of an elastic material so as to permit an expansion of said tank by water entering same through said inlet, and setting means connected to said movable pressure member for moving same away from said discharge pipe against the action of said biasing means into a position wherein said pinching action is eliminated and the outlet of the tank is opened for a discharge of water from said tank under the action of pressure accumulated in such an expanded tank.

2. An apparatus for flushing a toilet comprising: a closed tank having an inlet arranged for connection with a water pressure line and having an outlet, a discharge pipe, one end of said discharge pipe being connected to said outlet, the other end of said discharge pipe being arranged for connection with a toilet, at least a portion of said discharge pipe being made of elastic material, an abutment arranged adjacent said elastic portion of said discharge pipe, a movable pressure member arranged for cooperation with said elastic portion of said discharge pipe, adjustable biasing means connected with said movable pressure member, said biasing means being operable to urge said pressure member normally against said elastic portion of said discharge pipe so as to close same by a pinching action in cooperation with said abutment, adjusting means associated with said biasing means for adjusting same, at least a portion of the walls of said closed tank being made of an elastic material so as to permit an expansion of said tank by water entering same through said inlet, and setting means connected to said movable pressure member for moving same away from said discharge pipe against the action of said biasing means into a position wherein said pinching action is eliminated and the outlet of the tank is opened for a discharge of water from said tank under the action of pressure accumulated in such an expanded tank.
